(57) **CLAIM**

We claim the ornamental design for a mobile display device, as shown and described.

DESCRIPTION

FIG. 1 is a front perspective view of mobile display device, according to one embodiment;

FIG. 2 is a rear perspective view of a mobile display device of FIG. 1;

FIG. 3 is a front view of a mobile display device of FIG. 1; FIG. 4 is a rear view of a mobile display device of FIG. 1; FIG. 5 is a left side view of a mobile display device of FIG. 1, the right side view is a mirror image of the left side view of FIG. 5;

FIG. 6 is a top view of a mobile display device of FIG. 1; FIG. 7 is a bottom view of a mobile display device of FIG. 1; FIG. 8 is a front perspective view of mobile display device, according to a second embodiment;

FIG. 9 is a rear perspective view of a mobile display device of FIG. 8;

FIG. 10 is a front view of a mobile display device of FIG. 8; FIG. 11 is a rear view of a mobile display device of FIG. 8; FIG. 12 is a left side view of a mobile display device of FIG. 8, the right side view is a mirror image of the left side view of FIG. 12;

FIG. 13 is a top view of a mobile display device of FIG. 8; and, FIG. 14 is a bottom view of a mobile display device of FIG. 8. The mobile display device is shown with a symbolic break in its height. The appearance of any portion of the article between the break lines forms no part of the claimed design.

1 Claim, 12 Drawing Sheets
